(57) **CLAIM**

I claim the ornamental design for a trash can, as shown and described.

DESCRIPTION

FIG. 1 is a front view;

FIG. 2 is a top view;

FIG. 3 is a rear view (the same as a side view and an opposite side view);

FIG. 4 is a bottom view;

FIG. 5 is a perspective view;

FIG. 6 is an enlarged view of the feature from FIG. 5;

FIG. 7 is a perspective view of the can covered with a bag; and,

FIG. 8 is a perspective view of the can with the bag fixed by the feature of FIG. 5.

The broken line showing of a bag is included for the purpose of illustrating environment and forms no part of the claimed design.
